GUARD FOR AUTOMOTIVE VEHICLE LAMPS

Donald S. Bruce, Holliston, Mass., assignor to Signal-Stat Corporation, Brooklyn, N.Y., a corporation of New York

Filed Mar. 23, 1960, Ser. No. 59,844

Term of patent 14 years

(Cl. D48—32)

FIG. 1

FIG. 2

FIG. 4

FIG. 1 is a top plan view of a guard for automotive vehicle lamps, embodying my new design;

FIG. 2 is a side elevational view thereof;

FIG. 3 is a bottom plan view thereof; and

FIG. 4 is an end elevational view thereof.

I claim:

The ornamental design for a guard for automotive vehicle lamps, substantially as shown.
